UNITED STATES PATENT OFFICE

110,989

DESIGN FOR A FOOD CUTTER

Harold Van Doren, Toledo, Ohio, assignor to The Enterprise Manufacturing Company, of Pennsylvania, Philadelphia, Pa., a corporation of Pennsylvania

Application June 18, 1938, Serial No. 77,917

Term of patent 7 years

To all whom it may concern:

Be it known that I, Harold Van Doren, a citizen of the United States, residing at Toledo, Lucas County, Ohio, have invented a new, original, and ornamental Design for a Food Cutter, of which the following is a specification, reference being had to the accompanying drawings, forming a part thereof, in which

Fig. 1 is a perspective view of a food cutter showing my new design;

Fig. 2 is a front elevation thereof; and

Fig. 3 is a rear elevation thereof.

I claim:

The ornamental design for a food cutter, substantially as shown.

HAROLD VAN DOREN.
